 Company, Chicago, Ill., a corporation of Dela-
 ware

Application February 16, 1942, Serial No. 431,112

2 Claims. (Cl. 183—15)

This invention relates to a cleaner, and particularly to a cleaner adapted to remove impurities from air and other gases. It has for one object to provide a simple and effective mechanism for accomplishing the purpose mentioned.

Another object is to provide a cleaner of simple construction in which the inlet and outlet passages are combined in a single simple structure which is in effect the cover for the remaining mechanism.

Another object is to provide such a cover as a unitary assembly shaped to include the full inlet and outlet passages.

Another object is to provide a simple cover means for an oil bath air or gas cleaner.

Other objects will appear from time to time throughout the specification and claims.

This invention is illustrated more or less diagrammatically in the accompanying drawing, wherein:

Figure 1 is a vertical, sectional view of one form of the device.

Figure 2 is a transverse section taken at line 2—2 of Figure 1.

Figure 3 is a plan view of the cleaner, taken from the upper end.

Figure 4 is a partial vertical section illustrating a modified form.

Figure 5 is a fragmentary elevation illustrating the lock of Figure 4.

Like parts are indicated by like characters throughout the specification and the drawing.

The cleaner is usually made of sheet metal—for example, sheet steel—but it may be made of any other metal, and it may be made of materials other than metal. As shown, the cleaner includes an outer shell or wall 1. Adjacent its lower edge a ring-like member 2 is secured to the wall 1 by soldering, welding, or otherwise. This ring has a laterally turned portion 3 and a downwardly turned flange 4. Packing material 5 may be positioned within the space below the member 3. A pair of ears 6, 6 is positioned in a ring-like member 7 which is positioned adjacent the lower end of the wall 1 and which may be against the upper surface of the member 3. This ring may or may not be permanently positioned, as desired. A bail 8 is mounted in the perforated ears 6 and arranged for swinging. It may have spring loops 9, 9 formed in it, and may also carry a roller or anti-friction member 10.

A cup member 11 is arranged to be removably positioned at or about the lower end of the wall member 1. As shown, the cup is provided with a rounded bottom portion 12 within which a de-

pression 13 may be formed to receive the roller 10 or some equivalent member. Adjacent its upper end or edge the cup may be provided with a rolled portion 14 which contacts the packing 5, if any packing is present. The upper edge of the cup 11 may be of any desired form. It is preferably so arranged that it has a somewhat extended area of contact with or against the packing or against the under surface of the member 3 in case no packing is present.

The cup 11 is provided with an outwardly extending bead or depression 15 and with an adjacent, inwardly extending member 16 which forms on its upper surface a shoulder 17. Upon this shoulder is positioned a baffle supporting member 18. This baffle support may be held in place within the space provided by the bead 15 and against the shoulder 17 by a ring 19. The ring is crowded in this space and holds the support member 18. The ring may be sprung into place removably or may be held permanently in place, and obviously many other sorts of means may be used for holding the baffle support 18 against displacement.

Secured to the support 18 is a baffle member 20. As shown, this member contacts the support 18 by a number of feet 20a positioned away from the inner edge 21 of the support, and thus the inner edge 21 comprises in itself a baffling member, and there is a clearance between the upper edge of the member 20 and the under surface of the support 18. The baffle 20 is provided with a raised central portion 22 and is provided with a plurality of downwardly bent portions 23 which provide or form passages 24. A member 25 may be secured to the baffle 20 beneath the raised central portion 22.

Positioned symmetrically and centrally with relation to the outer wall 1 is an inner wall and passage member 27. At or adjacent its lower end, this member is secured to and supported from the outer wall member 1 by a spider 28 which is provided with an outer annular portion 29 which is secured to the ring 2. It is provided with an inner annular portion 30 which might be secured to the inlet passage 27, but in the particular form of this invention here shown it is secured to the cylindrical portion 31 of a baffle 32 which as shown is provided with an upwardly curved terminal portion 33. Obviously the baffle structure including the members 31, 32, and 33 could be made unitary with the central tubular portion 27.

Adjacent its upper end the tube 27 has secured exteriorly an annular portion 34 of a downwardly

facing and downwardly curved baffle 35. This baffle also serves to limit and position an annular member 36 which is perforated or formed of mesh material and which prevents upward displacement of the filtering material 37, which as shown substantially fills the space defined by the wall 1 and the tube 27 and lies above the spider 28 and below the member 36. This material may be of almost any desired nature. One suitable material is metal wool, or other finely divided metal, and while copper is suitable for this purpose, many other metals and many non-metallic filtering materials may be used without departing from the spirit of the invention.

At its upper end the central tube 27 is cut off diagonally, as indicated at 38, so that one side is of greater length than the opposite side. Secured at or near the upper end is the annular portion 39 of a closing member 40. This member is inclined, as shown, and the portion 40 is joined to the portion 39 by a curved portion 41, the curvature of which varies as shown. The portion 40 serves as a closure or cover for the upper end of the annular space defined between the outer wall 1 and the central inlet passage member 27, and it is provided with an upturned flange 40a which is secured to the inner face of the outer wall 1 by welding, soldering, or otherwise. Preferably on the side of the cleaner to which the member 40 is closest to the top of the assembly, an outlet passage member 42 is secured in place. As shown it is secured to an outwardly bent portion 43 of the side wall 1. On the opposite side, where the member 40 is at its lowest point, an inlet passage connection member 44 is secured to an outwardly bent portion 45 of the outer wall member 1. A cover member 46 is provided with a downwardly bent annular flange 47 by means of which it is secured to the upper end of the wall member 1. While the outlet passage connecting member 42 and the inlet passage connecting member 44 are shown as diametrically opposite to each other, it is to be understood that they need not be so arranged. It is ordinarily convenient to have each of these members secured to that portion of the housing which provides the most space for it, and thus it is convenient to have the inlet passage opposite the lowest edge of the member 40, and it is convenient to have the outlet passage member connected opposite the highest edge of the member 40, but the invention is not limited to this exact arrangement.

The member 40 has been shown and described as being generally flat except for the perforation of the curved portion 41. It need not, however, be flat, and it can be of almost any shape so long as it provides a cover for the annular space defined by the members 1 and 27, and so long as it does not make the attachment of the members 42 and 44 inconvenient or impossible. It might be flat, as shown, or curved, or might have flat portions and curved portions.

While the device of this invention may be held in place in any desired manner, it is convenient to provide a bracket, and the member 48 is such a bracket member. As shown it is secured to the outer wall of the housing at any desired location, and is provided with two laterally extending members or portions 49 and 50, which are suitably shaped to receive some attaching means. Thus notches 51 are provided. Of course perforations might be substituted for the notches, and the invention is in no way limited to the use of the bracket nor to any particular type of

bracket. That which is shown is merely one convenient bracket form.

In the modified form of Figures 4 and 5 the parts are substantially the same as those described in connection with Figures 1, 2, and 3. The main change is the provision of the bayonet lock mechanism and the associated parts. Thus there is secured to the ring-like portion 30, which forms a part of the spider assembly, one or more pins 52 which are adapted to extend through and engage bayonet slots 53 which are formed in the tube or passage member 27. An extension 54 is secured to the generally cylindrical member 31, which may be attached to or formed as a part of the baffle 32, and this extension is provided with an offset or outwardly flared portion 55.

The use and operation of the invention are as follows:

The cleaner illustrated herewith may be used in many places and for many purposes, where it is desired to clean air or gas and to remove solid matter and other impurities from it. In the particular form here shown, however, it is adapted to be used as an air cleaner for an internal combustion engine, and to be used in removing dust and other impurities from the air before it is drawn into the engine or the carburetor. It is intended to operate in a substantially upright position, and the cup 11 is filled with oil to the level indicated. The inlet connection 44 may be joined to any form of inlet passage member, or may serve itself as the inlet passage member. The outlet member 42 may be connected directly to the engine or to the carburetor, or may be connected to a passage member which leads to the engine or to the carburetor.

Assuming now that the device is in the position shown, that it is connected to the engine or carburetor, and that oil is in the cup to the level indicated, when the engine is started, air will enter through the member 44 and pass downwardly through the tube 27. It will then be carried upwardly by the baffle 20 and by the baffle 32, 33. As the air moves upwardly, oil will be drawn through the openings 24 and will be carried along with the upwardly rising air. Some of the oil will be stopped by the baffling portion 21 of the member 18 and will be discharged over the upper edge of the baffle 20 carrying with it such impurities as it has collected or entrained, because as the oil tends to flow upward and outward along the baffle 20 it strikes the overhanging or inwardly projecting edge 21 and is to some degree prevented from passing upward. Some of the oil is, however, carried upwardly with the oil through the openings in the spider 28, and upwardly to a greater or less degree into the filtering material 37. As the suction of the engine varies, the degree or distance to which the oil is withdrawn from the cup and carried upwardly into the filter material also varies. When the engine stops and suction is discontinued, the oil then drains back through the filter material onto the baffle 20 and through the openings 24 into the main body of oil within the cup.

The function of the oil is to catch and retain impurities which have entered with the air, and the oil which is exposed to the current of air anywhere in the system will retain the impurities. As the oil flows or drains or otherwise moves downwardly from the filter material it carries back some or all of the impurities which it has picked up, and these impurities to a large degree

collect in the cup so that gradually during use the oil becomes more or less filled with impurities.

When it is necessary to clean the oil, the bail is moved from the position shown to a position in which it no longer holds the cup in place. The cup is then removed and the oil is discharged for cleaning or replacement. As the baffle assembly is mounted in the cup it goes with the cup, and if it is necessary to remove the baffle assembly from the cup, that is done by removing the ring 19 which then permits the carrier 18 to be withdrawn and with it, the baffle 20. When the cup and baffle are removed, the spider 28 which supports the filter material 31 may or may not be removed with it. Thus the spider ring 29 may be permanently secured to the cup 11 so that it moves with it or it may not. If it is permanently secured to the cup, then when the cup is removed the spider and the baffle 32, 33 come with it. In the form shown in Figure 1 on special arrangement is made at the end of the inlet tube 27 for engagement with the baffle ring 31 or the spider ring 30 or any of the parts adjacent this end of the device, and they may either fit together with a friction fit or be permanently secured in any desired manner. In the form of Figure 4, however, the structure differs, and the baffle is secured to the spider ring and the latter carries one or more pins which engage in suitable notches formed in the bottom of the tube 27, and thus when that part of the device is to be removed from the tube, it is given a slight turn to move the pins into the position in which they can be readily freed from or withdrawn from the slots or notches. Also in the form of Figure 4, when the assembly is moved into the position shown in that figure the filter material may be somewhat raised, as shown, and the edge of the spider ring which is flared away from the tube 27 is effective to prevent clogging or catching of the filter material which might otherwise interfere with the insertion or re-insertion of the device. The modified construction of Figure 4 is therefore an alternate form and one which possibly makes the assembly and re-assembly of the device simpler and less likely to interference from

the filter material than does the form of Figure 1. Both forms, however, are advantageous.

I claim:

1. In combination in an air cleaner, a housing 6 and an inlet passage member positioned within said housing, and forming with said housing an air passage, a cover completely closing the upper end of said housing and in continuous contact therewith, a partition within said housing, an inlet opening in the wall of said housing above the point of contact of said partition with said housing wall, and an outlet opening in the wall of said housing below the point of contact of the partition with the housing wall, and a cup-like member 10 removably closing the bottom of said housing, and a member positioned to move with said cup and including an annular part positioned to contact said inlet passage member, said annular part being flared outwardly adjacent its upper end, and removable latch means positioned partly on said outlet passage member and partly on said annular member, and adapted to secure the two removably together.
2. In combination in an air cleaner, a housing 25 and an inlet passage member positioned within said housing, and forming with said housing an air passage, a cover completely closing one end of said housing, the periphery of said partition being in continuous contact with said housing, a 30 partition within said housing, an inlet opening in the wall of said housing above the point of contact of said partition with said housing wall, and an outlet opening in the wall of said housing below the point of contact of the partition with the housing wall, said two openings lying generally within the same planes, and a cup-like member 35 removably closing the bottom of said housing, and a member positioned to move with said cup and including an annular part positioned to contact said inlet passage member, said annular member being flared outwardly adjacent its upper end, and bayonet lock means positioned partly on said inlet passage member and partly on said annular member, adapted to secure the two 40 removably together.

DALE L. BENNETT.
ALEX J. McALLISTER.
